Primary Examiner — Paula Greene(57) **CLAIM**

The ornamental design for a communications headset, as shown and described.

DESCRIPTION

This application is related to co-pending U.S. Design application Ser. Nos. 29/547,974, titled "Communications Headset", and 29/547,989, titled "Microphone Boom for a Communications Headset".

FIG. 1 is a front-right perspective view of a communications headset showing my new design;

FIG. 2 is a back-left perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The communications headset is shown with symbolic break lines. The appearance of any portion of the article between the break lines forms no part of the claimed design.

1 Claim, 8 Drawing Sheets# US D784,290 S
